(57) **CLAIM**

The ornamental design for a temperature sensor label, as shown and described.

DESCRIPTION

FIG. 1 is a left upper perspective view of a temperature sensor label.

FIG. 2 is a front view of the temperature sensor label of FIG. 1.

FIG. 3 is a rear view of the temperature sensor label of FIG. 1.

FIG. 4 is a left side view of the temperature sensor label of FIG. 1 of which the right side is a mirror image; and, FIG. 5 is a top view of the temperature sensor label of FIG. 1 of which the bottom view is a mirror image.

1 Claim, 4 Drawing Sheets

FIG. 1

FIG. 2

FIG. 3

FIG. 4

FIG. 5
